UNITED STATES PATENT OFFICE.

JOHN R. WARREN, OF GRAND RAPIDS, MICHIGAN, ASSIGNOR TO HIMSELF AND
DONALD J. CAMPBELL, OF MUSKEGON HEIGHTS, MICHIGAN, AND CHARLES
E. JOHNSON, PAUL R. BEARDSLEY, AND CARL P. DAMM, ALL OF MUSKEGON,
MICHIGAN, TRUSTEES.

ROTARY VALVE.

1,410,232.

Specification of Letters Patent. Patented Mar. 21, 1922.

Application filed August 17, 1921. Serial No. 492,954.

To all whom it may concern:

Be it known that I, JOHN R. WARREN, a citizen of the United States, residing at Grand Rapids, in the county of Kent and State of Michigan, have invented new and useful Improvements in Rotary Valves, of which the following is a specification.

The present invention relates to rotary valves, such as are employed in connection with internal-combustion engines; and its object is to provide a valve of that character having a cast outer member and an inner, passage-forming, member a portion of which is embedded in the outer member in the casting thereof.

This and any other objects hereinafter appearing are attained by, and the invention finds preferable embodiment in, the structures hereinafter particularly described in the body of this specification and illustrated by the accompanying drawings, in which:—

Figure 1 is an axial sectional view of a rotary valve;

Figure 2 is a left-hand end view thereof;

Figure 3 is a right-hand end view of the same;

Figure 4 is a transverse sectional view of the same taken on a plane corresponding to line 4—4 of Figure 1;

Figure 5 is a side view of the inner member of said valve and an axial sectional view of outwardly extending annular portions thereof and of the sand core of the mold wherein the outer member of the valve is so cast as to imbed such annular portions within it;

Figure 6 is a like view of a portion of said sand core and of the valve's outer member;

Figure 7 is a view similar to Figure 4, but showing a modified construction; and

Figure 8 is a cross-sectional view of another valve embodying my invention.

In the embodiment of the invention chosen for illustration by the drawings and for detailed description in the body of this specification, a rotary valve for controlling the intake of the engine-operating fluid to the cylinders of an internal-combustion engine and the exhaust of the products of combustion therefrom is shown, such valve as

shown in Figures 1, 2, 3, 4, 5, 6 and 7 controlling three such cylinders (not shown), a pair of such valves being employed in connection with a six-cylinder engine. This valve comprises two members; first, an inner cylindrical member 1 preferably formed of sheet steel and comprising the outer shell 2 and inner walls 3 whereby the passages 4 are formed for expulsion of the products of combustion through the valve from the exhaust ports 5 communicating with the three engine cylinders; and second, the cast outer cylindrical hollow member 6, whose outer surface bears rotatably in the valve's chamber, not shown, this outer member surrounding said inner member 1 and being spaced therefrom to provide a passage 7 for supplying from the annular intake port 8 the engine-operating fluid to the cylinders through the ports 9. The two portions of the outer member 6 on the opposite sides of the annular intake port 8 are supported in connection with the inner member 1 and held in said spaced relation thereto by said inner member's outwardly extending supporting portions, which comprise the annular portions 10, 11 adjacent the ends respectively of the inner member 1 and preferably formed of separate pieces therefrom and being joined thereto as by welding. These annular portions close the ends of the intake passage 7. Such supporting portions also comprise the flanges 12 surrounding the exhaust ports 5 and separating them from the intake passage 7. These two members 1 and 6 of the valve are joined together by casting the outer member 6 around a sand core 13 surrounding the inner member 1, the outer edges of the supporting portions 10, 11, 12 of the inner member extending outwardly beyond the sand core and being embedded in the casting operation of the outer member 6 within it. Some of these supporting portions of the inner member, as 12 are shown as extending not only radially outwardly from, but toward an end of, the inner member 1. The inner walls 3 of the inner member 1 may be formed with flange portions 14 as shown in Figure 7 which flanges are joined, as by welding, to the inner surface of the inner member's shell 2.

In Figure 8 another form of valve is

shown in cross section embodying the basic principle of my invention. In this view the valve has ports 16, 17, a passage 18 between said ports being formed by the sheet metal 5 inner member 19 whose ends 20 are embedded in the cast outer member 6¹ in the casting thereof. To effect such casting the sand core indicated at 13¹ is formed about the inner member 19 leaving its ends 20 extending outwardly from the sand core to be embedded in the outer member as aforesaid.

The invention being intended to be pointed out in the claims, is not to be limited to or by details of construction of the particular 15 embodiment thereof illustrated by the drawings or hereinbefore described.

I claim:

1. In a rotary valve for internal-combustion engines; an inner hollow cylindrical member having an outwardly extending supporting portion, and ports communicating with the engine's cylinder; a cast outer hollow cylindrical member spaced from said inner member and rotatably bearing in the valve's chamber and having ports communicating with the engine's cylinder and having embedded in said outer member in the casting thereof said portion of said inner member.
2. In a rotary valve for internal-combustion engines; an inner hollow cylindrical member having an outwardly extending supporting portion of separate piece therefrom and joined thereto, and ports communicating with the engine's cylinder; a cast outer hollow cylindrical member spaced from said inner member and rotatably bearing in the valve's chamber and having ports communicating with the engine's cylinder and having embedded in said outer member in the casting thereof said portion of said inner member.
3. In a rotary valve for internal-combustion engines; an inner hollow cylindrical member having an outwardly extending supporting portion annularly shaped of separate piece therefrom and joined thereto,

and ports communicating with the engine's cylinder; a cast outer hollow cylindrical member spaced from said inner member and 50 rotatably bearing in the valve's chamber and having ports communicating with the engine's cylinder and having embedded in said outer member in the casting thereof said portion of said inner member.

4. In a rotary valve for internal-combustion engines; an inner hollow cylindrical member having ports communicating with the engine's cylinder and a supporting portion annularly shaped of separate piece 60 therefrom and joined thereto and extending outwardly from and toward an end of the valve; a cast outer hollow cylindrical member spaced from said inner member and rotatably bearing in the valve's chamber and 65 having ports communicating with the engine's cylinder and having embedded in said outer member in the casting thereof said portion of said inner member.

5. In a rotary valve for internal-combustion engines; an inner hollow cylindrical member having ports communicating with the engine's cylinder and outwardly extending flanges surrounding said ports; a cast outer hollow cylindrical member spaced 75 from said inner member and rotatably bearing in the valve's chamber and having ports communicating with the engine's cylinder and having embedded in said outer member in the casting thereof said flanges of said 80 inner member.

6. In a rotary valve for internal-combustion engines; an inner member having a passage communicating with the engine's cylinder; a cast outer cylindrical member 85 rotatably bearing in the valve's chamber and having embedded in said outer member in the casting thereof an outwardly extending portion of said inner member.

In testimony whereof I have hereunto set 90 my hand at Grand Rapids, Michigan, this 8th day of August, 1921.

JOHN R. WARREN.
